UNITED STATES PATENT OFFICE.

DORR E. FELT, OF CHICAGO, ILLINOIS.

DUPLICATE PRINTING MECHANISM FOR ADDING-MACHINES.

SPECIFICATION forming part of Letters Patent No. 693,958, dated February 25, 1902.

Application filed August 17, 1899. Serial No. 727,490. (No model.)

To all whom it may concern:

Be it known that I, DORR E. FELT, a citizen of the United States, residing in Chicago, in the county of Cook and State of Illinois, have 5 invented a new and useful Improvement in Duplicate-Printing Mechanisms for Adding-Machines, of which the following is a specification.

This invention is a modification of and in 10 some respects an improvement upon the duplicating-printing mechanism for calculating and other type-writing machines shown in the patent to me, No. 590,972, of October 5, 1897. In my said patent I duplicated the 15 work by the use of a single set of type and a single ribbon, and without the employment of carbon or manifolding paper, by making the duplicate copy upon thin transparent paper and feeding it and the paper for the 20 original upon opposite sides of the ribbon, so both papers were impressed by the same impact of the type or type-hammer, the characters being thus printed in reverse upon the back of the duplicate sheet, but showing 25 through it, so as to be distinctly readable upon the front. I also provided in said patent means for separating the paper strips as they approached the printing-center and for 30 guiding them into position on opposite sides of the ink-ribbon.

In my present invention I still employ a single ink-ribbon; but instead of printing from both sides of the ribbon, as before, I now double the ribbon upon itself in front of 35 the type and print from both courses thereof, one copy from each. In other words, both the ribbon-spools are located at the same side of the machine, and the ribbon is led from one of the spools past the printing-point to and 40 around a roller at the other side of the machine, and thence back and again past the printing-point to the other spool. One of the strips of paper is fed between the two courses 45 of the ribbon and the other outside of them, and proper guides are provided for starting 50 the strips of paper in their proper channels. By these means I am enabled to make both impressions direct instead of one direct and one reverse, as in the patented machine, and thus render unnecessary the use of transparent paper for either of the paper strips. This and other features of my invention are

fully set forth below and also illustrated in the accompanying drawings, in which latter--

Figure 1 is a plan of that portion of the 55 machine to which my invention relates, showing the ribbon and the type-segments. Fig. 2 is a front elevation of the parts shown at Fig. 1. Fig. 3 is a vertical section showing the same parts in position for printing. Figs. 60 4 and 5 are sections on the lines 4 4 of Fig. 2; and Figs. 6, 7, and 8 are sections on the line 6 6 of Fig. 2, giving different positions of the paper and ink-ribbon guides. Fig. 9 is a detail section on the line 9 9 of Fig. 2. Figs. 65 10 and 11 are detail perspectives showing the ribbon-guides in different positions. Fig. 12 is a view similar to Fig. 9, showing the parts in a different position. Fig. 13 is a section on the line 13 13 of Fig. 12. Fig. 14 is a detail 70 perspective of one of the parts.

In said drawings, A A represent segments each carrying a series of type and pivoted at A' and positioned to bring the proper type to the printing-line by rods A², joined to the 75 gooseneck extensions A³, the latter rigidly connected to the segments, though they are spaced farther apart than the segments, so as to bring them in line with the keys from which they are actuated. The segments shown 80 at Fig. 3 is in the position in which it will print its upper character.

B is one of the hammers for impressing the paper and ribbon on the type, there being 85 one such for each type-segment.

C and C' are the paper-feed rolls, acting to feed both strips W Y of the paper to the printing mechanism from supply-rolls. (Not shown.)

D D' are the ink-ribbon spools, actuated in 90 the customary manner by pinions, some of which are shown at D² D³ D⁴. The pinions D² and D³ are fast on shaft D⁵, supported in swinging arms D⁶ and controlled as to position by the lever D⁷. Both the spools are located at the same side of the machine, as clearly shown at Fig. 1, and the ribbon E passes from spool D around guide-roller D⁸, thence across the machine and past the printing-center to a second guide-roller D⁹, and 100 thence from in front of a guide-stud D¹⁰ back past the type to the other spool D'. Two separate and parallel courses or portions E' and E² of the ribbon are thus positioned be-

tween the type and hammers, and each of them may be utilized to print on one of the strips of paper, as will be fully explained hereinafter.

- 5 In order to utilize the two parallel courses of the ribbon for printing upon separate strips of paper, suitable means are provided for separating the courses of the ribbon, so as to permit the entrance of one of the strips of paper 10 between them. These means consist in part of two parallel flat spring-plates F and F', arranged across the front of the type-segments and cut out at their centers, as plainly shown at Figs. 2, 10, and 11, so as to expose the ribbon, while their upstanding end wings F² act as guides to the ribbon. The plates are preferably secured together along their bottom line, so that both move together, and they are firmly attached at one end to a stationary 20 part of the machine, as seen at F³, the other end being free to be forced forward by a hand-lever F⁴, mounted on the cross-shaft F⁵. One of the ribbon courses—that indicated at E'—moves between the wings of the plates F F', and the other course E² thereof moves between the back plate F' and the stationary abutments F⁶ and F⁷, arranged one at either 25 side of the type-segments, as seen at Figs. 1 and 2.
- 30 The lever F⁴ is intended only for momentary use while entering one of the paper strips between the ribbon courses E' and E², and consequently it is adapted to swing forward when actuated by the operator a limited 35 distance and in so doing by its engagement with the spring-plates or the extension F⁸ on one of them to force their free ends forward, and thus widen the space between the ribbon courses and allow the initial end 40 of the paper strip Y to enter between them. This operation will be clearly understood from Figs. 10 and 11, Fig. 10 showing the plates in their normal position, with the ribbon courses together, and Fig. 11 showing them as bent 45 forward, as just described, and as moving the course E' away from course E² to form the opening for paper Y. As soon as strip Y has been entered between the ribbon courses the lever F⁴ is released by the operator and returns to its normal position under the power 50 of spring F⁹, attached to the guard-plate G, fast on said shaft F⁵ and located at the other side of the printing-center. Said plate G and a companion plate G', which, however, is 55 loose upon the shaft F⁵ instead of being fast on it, as is the case with plate G, are located below the spring ribbon-guide F and in such proximity to the paper-feed rolls as to enable the plates to direct the paper properly with reference 60 to the ribbon. The plate G is controlled by its shaft F⁵, and consequently swings forward whenever the lever F⁴ is moved forward, as hereinafter set forth, and it also swings in the same direction whenever plate G' swings forward by reason of the engagement of pin G², carried by shaft F⁵, and the projection G³, carried by said plate. Plate G' is actuated in

these movements by a hand-lever G⁴, attached to or in one piece with it, and is returned by a spring G⁵. A pivoted pawl G⁶ serves to lock 70 lever G⁴ in its forward position, (shown at Fig. 8,) being swung automatically into position behind the lever, so as to prevent its return, by attaching it to the other end of said spring G⁵. The lock thus effected is released by lever F⁴ when it is next operated, as said lever then encounters the point or projection G⁷ on the pawl and turns the latter sufficiently to release lever G⁴.

The paper strips are both cut diagonally at 80 their initial ends, and when two strips are used they should be thus cut in opposite directions, (see Fig. 2,) so that when advanced by the feed-rolls the long side of strip W strikes the plate G and the long side of strip Y strikes plate G'. These plates are located at opposite sides of the vertical center of the machine, and each is thus adapted to act on the advance portion of one of the strips. When in position for use without duplicating and with 85 one strip of paper, they are both inclined forward, so that the paper will be directed by them to the front or outside of the ribbon-guide F; but if it is desired to duplicate, the operator actuates lever F⁴, thereby throwing 90 forward plate G, but leaving plate G' in the position of Figs. 6 and 7, and holds said lever against returning while he feeds the paper upward. Plate G will now direct strip W forward of the ribbon-guide F, and plate G' will 95 act upon the advance point of strip Y and direct it between the two courses of the ribbon. Having once started the papers in this manner, they will continue to feed one in front of course E' and the other between the two 100 courses of the ribbon so long as desired. If the operator desires to stop duplicating, he preferably severs strip Y at some point between the feed-rolls and the supply-roll, and then sets lever G⁴ forward, throwing both 105 guide-plates G and G' forward into position to direct the paper, whether one or both strips, 110 forward of the ribbon E'.

Of course the paper strip which passes between the two courses of ribbon will be printed 115 upon the back as well as on front, but this will not ordinarily be objectionable.

Figs. 4 and 6 show the positions of the paper and ribbon guides when entering two strips of paper for duplicating. Figs. 5 and 7 show 120 the positions after the lever F⁴ has been released and the parts have returned to the positions occupied by them while the printing in duplicate is being done. Fig. 8 shows the position of the lever G⁴ and guide G' when set 125 for operation without duplicating.

While the machine illustrated is specially intended for the production of both an original and a duplicate record of the work done by it, it will be understood that if no duplicate is desired it can be readily and instantly changed so as to produce only an original by throwing lever G⁴ to its forward position in which it is automatically locked, as above 130

stated; also, that while I have shown only a single ribbon it will be understood that the ribbon-separating devices and the paper-guiding devices may be used in machines employing two separate ribbons, each passing but once past the printing-center.

The lever F^4 is loosely mounted on the shaft F^5 , but actuates the latter when it is moved forward, as above stated, by reason of the contact of the pin F^{10} , carried by the shaft, with the projection F^{11} , carried by the lever. A stop F^{12} limits the forward movement of the lever.

I claim—

15 1. A duplicating printing device comprising a single set of type, an ink-ribbon doubled on itself each fold adapted to make an impression on its respective sheet of paper and by the same type, and means for operating the printing mechanism and automatically feeding the paper and inking ribbon.

25 2. The combination of a paper-feeder for feeding two layers of paper in one direction, a doubled inking-ribbon extending transversely to the direction of movement of the paper and along the printing line or center, one strand of the ribbon lying between the said layers of paper and the other strand outside of one of said layers, means for feeding 30 the said strands in opposite directions transversely to the direction of the paper-feed, a set of printing-type acting at said line or center to print duplicate impressions on said paper, and mechanism for causing an impression by said type.

35 3. The tabulating or type-writing machine having a single ink-ribbon doubled on itself so that two courses of it will be passing the printing-center at the same time, and also 40 provided with means other than the paper being written upon for separating said courses, substantially as specified.

45 4. The tabulating or other type-writing machine, having two parallel and closely-associated and automatically-operated ribbons passing the printing-center at the same time, and adapted to make direct impressions upon different sheets or strips of paper, and also having means other than the paper being 50 written upon for temporarily separating the ribbons to admit one of the paper sheets or strips between them, substantially as specified.

55 5. The tabulating or other type-writing machine, having two parallel and closely-associated ribbons passing the printing-center at the same time, and adapted to make direct impressions upon different sheets or strips of paper, and a guide for one of the ribbons, 60 movable so as to carry its ribbon temporarily away from the other ribbon and thus give entrance for the paper between the ribbons, substantially as specified.

65 6. The tabulating or other type-writing machine, having two parallel and closely-associated ribbons passing the printing-center at the same time, and adapted to make direct im-

pressions upon different sheets or strips of paper, and also having a guiding device F F' movable so as to deflect one of the ribbons 70 away from the other and give entrance to the paper between the ribbons, substantially as specified.

7. The tabulating or other type-writing machine, having two parallel and closely-associated and automatically-operated ribbons passing the printing-center at the same time, and adapted to make direct impressions upon different sheets or strips of paper, and also having means for feeding two strips of paper 80 and guiding means for directing one of said strips between the ribbons, substantially as specified.

8. The tabulating or type-writing machine having two parallel or closely-associated ribbons passing the printing-center at the same time, and wherein are combined means for supporting and feeding said ribbons, means other than the paper for temporarily separating said ribbons at the printing-center, means 90 for feeding two strips of paper and means for directing one of said strips between the separated ribbons, substantially as specified.

9. The tabulating or other type-writing machine having two parallel and closely-associated ribbons passing the printing-center at the same time, and wherein are combined means for supporting and feeding said ribbons, means for temporarily separating the ribbons at the printing-center, means for 100 feeding two strips of paper, and guides acting to separate the strips and to direct one strip outside of and the other strip between the ribbons, substantially as specified.

10. The tabulating or other type-writing machine having two parallel and closely-associated ribbons passing the printing-center at the same time, and wherein are combined means for supporting and feeding the ribbons, means for temporarily separating the ribbons 110 at the printing-center, means for feeding the paper, movable guides for separating and directing the paper strips so that one moves outside of and the other between the ribbons, and means for controlling said guides, substantially as specified.

11. The tabulating or other type-writing machine having two parallel and closely-associated ribbons passing the printing-center at the same time, and wherein are combined 120 means for supporting and feeding the ribbons, means for temporarily separating the ribbons at the printing-center, means for feeding the paper, movable guides for separating and directing the paper strips so that one moves 125 outside of and the other between the ribbons, and a lever acting both to cause the separation of the ribbons and the positioning of said guides, substantially as specified.

12. The tabulating or other type-writing machine having two parallel and closely-associated ribbons passing the printing-center at the same time, and wherein are combined means for supporting and feeding the ribbons,

means for temporarily separating the ribbons at the printing-center, means for feeding the paper, movable guides for separating and directing the paper strips so that one moves 5 outside of and the other between the ribbons, a lever for positioning both said guides in the same position, a pivoted pawl or latch for locking said lever in its acting position, and means for releasing said pawl, substantially 10 as specified.

13. The tabulating or other type-writing machine having two parallel and closely-associated ribbons passing the printing-center at the same time, and wherein are combined 15 means for supporting and feeding the ribbons, means for temporarily separating the ribbons at the printing-center, means for feeding the paper, movable guides for separating and directing the paper strips so that one moves 20 outside of and the other between the ribbons, a lever for positioning both said guides in the

same position, a pivoted pawl or latch for locking said lever in its acting position, said pawl being releasable by a second lever included in the means for separating the ribbons, substantially as specified. 25

14. The combination with the paper-guides G and G', of a lever fast upon the shaft carrying said guides, a second lever attached to the loose guide, and a pawl for locking said last- 30 mentioned lever in one position, said pawl being released by the first-mentioned lever, substantially as specified.

15. The combination of guides G G', the rock-shaft on which they are mounted, the 35 levers F⁴ and G⁴ and the pawl-locking lever G⁶ and released by lever F⁴, substantially as specified.

DORR E. FELT.
